UNITED STATES PATENT OFFICE

98,859

DESIGN FOR A BOTTLE

Charles B. Garwood, Linthicum Heights, Md., assignor to Carr-Lowrey Glass Co., Baltimore, Md.

Application January 9, 1936, Serial No. 60,490

Term of patent 14 years

To all whom it may concern:

Be it known that I, Charles B. Garwood, a citizen of the United States, residing at Linthicum Heights, in the county of Anne Arundel and State of Maryland, have invented a new, original, and ornamental Design for a Bottle, of which the following is a specification, reference being had to the accompanying drawing, forming part thereof.

The four sides of the bottle are identical.

I claim:—

The ornamental design for a bottle, as shown and described.

CHARLES B. GARWOOD.
